R. L. O'NEIL

BASE FOR A LOUD SPEAKER OR SIMILAR ARTICLE

Filed Sept. 29, 1923

Raymond L. O'Neil,
Inventor,
By his Attorney,
Henry J. Lueke.

Patented Mar. 24, 1925.

Des. 66,873

UNITED STATES PATENT OFFICE.

RAYMOND L. O'NEIL, OF WEEHAWKEN, NEW JERSEY.

DESIGN FOR A BASE FOR A LOUD SPEAKER OR SIMILAR ARTICLE.

Application filed September 29, 1923. Serial No. 7,365. Term of patent 14 years.

To all whom it may concern:

Be it known that I, RAYMOND L. O'NEIL, a citizen of the United States, residing in Weehawken, county of Hudson, State of New Jersey, have invented a new, original, and ornamental Design for a Base for a Loud Speaker or Similar Article, of which the following is a specification, reference being had to the accompanying drawing, forming part thereof.

The figure is a perspective view of a base for a loud speaker or similar article, showing my new design.

I claim:

The ornamental design for a base for a loud speaker, or similar article, as shown.

RAYMOND L. O'NEIL.

Witnesses:

HENRY J. LUCKE,
ELIZABETH C. BRENNAN.
